UNITED STATES PATENT OFFICE.

JOHN JOHNSTON, OF WOONSOCKET, RHODE ISLAND.

FRICITION DEVICE FOR SHUTTLES.

1,079,009.

Specification of Letters Patent. Patented Nov. 18, 1913.

Application filed January 6, 1913. Serial No. 740,297.

To all whom it may concern:

Be it known that I, JOHN JOHNSTON, a citizen of the United States, residing at Woonsocket, in the county of Providence and State of Rhode Island, have invented a new and useful Improvement in Friction Devices for Shuttles, of which the following is a specification.

This invention relates to certain new and useful improvements in friction devices for shuttles.

The primary object of the invention is to provide a holder for the felt or other friction media which can be easily and quickly applied to or removed from the shuttle.

Further the invention aims to provide a holder of simple and economical construction which can be easily bent to secure the friction media thereto.

20 In the drawings—Figure 1 is a fragmentary perspective view of a shuttle equipped with the present invention. Fig. 2 is a fragmentary vertical sectional view. Fig. 3 is a detached perspective view of the friction device. Fig. 4 is a plan view of the blank from which the holder is formed, and Fig. 5 is a plan view of the friction element proper.

The invention broadly consists of a metal-
30 lie holder and friction material, which latter is secured to the holder by bending the latter so as to clamp the friction material between the bent portions of the holder, and to this end a metal blank of substantially rectangular form, as shown in Fig. 4 of the drawings, is provided with a central longitudinal slet 1. The blank is then bent over upon itself on the lines 2-2 of Fig. 4, whereby it will be seen that two U-shaped
35 parts 3 are provided, which parts are connected at their free upper ends. As depicted in Fig. 5 of the drawings a piece of felt or other suitable material is provided with a central cut 5, through which the thread T
40 passes. The piece of felt 4 is placed on one of the parts 3, and the other part 3 is then bent to engage the opposite side of the piece of felt 4, whereby it will be seen that the felt is clamped by and between the two
45 parts 3, the felt extending across the space between the legs of the U-shaped part 3, and since the cut 5 of the piece of felt 4 opens outwardly at the free upper ends of

the legs of the U-shaped parts 3, it will be seen that the thread can be introduced into the cut 5 by merely moving the thread downwardly into said cut. The throat of the shuttle is formed with confronting vertical cut-out portions 6 to provide guides for the opposite sides of the holder, the holder having its lower end placed in the guide 6 and moved down thereinto. An opening 7 extends through the bottom of the shuttle and the upper end of the opening terminates adjacent to the bottom of the holder, so that any suitable instrument can be introduced into the opening 7 to drive the friction device out of its guideways, whereupon a new friction device may then be placed into position, or the piece of felt 4 removed from the dislodged friction device, and a new piece of felt substituted, whereupon the holder may be replaced in the guideways.

From the above it will be obvious that the 75 friction devices can be easily, quickly and economically produced, and since the holder itself frictionally secures, by clamping, the piece of felt thereto, the latter is not only rigidly secured in the holder, but in addition no other means is required to secure the 80 felt to the holder.

Having thus described my invention, claim as new and desire to secure by Letters Patent,--

A friction device for shuttles formed of a blank of substantially rectangular contour which has a single central longitudinal slot spaced from the ends and sides of the blank, said blank being bent transversely of its center to form a pair of similar U-shaped parts which latter are connected to each other at their upper ends and a piece of felt arranged between the legs of said U-shaped parts and having a cut therein which leads downwardly from the upper end of the felt, the base ends of said U-shaped parts extending on opposite faces of the lower end of the felt. 95

In testimony whereof I have signed my name to this specification in the presence of two subscribing witnesses.

JOHN JOHNSTON.
